CLAIM

The ornamental design for a comb having a cavity for holding a nail file or the like, as shown.

DESCRIPTION

FIG. 1 is a perspective view of a comb having a cavity for holding a nail file or the like;

FIG. 2 is a front end view thereof;

FIG. 3 is a rear end view thereof;

FIG. 4 is a top plan view thereof;

FIG. 5 is a right side elevational view thereof;

FIG. 6 is a left side elevational view thereof; and

FIG. 7 is a bottom plan view thereof.
